TELEPHONE SYSTEM

Max Langer, Berlin-Hermsdorf, Germany, assignor to Siemens & Halske Aktiengesellschaft, Siemensstadt, near Berlin, Germany

Application March 21, 1932, Serial No. 600,284, and in Germany March 27, 1931

10 Claims. (Cl. 179—18)

The present invention relates to a circuit arrangement for switches in telephone systems over which may be reached lines of a different traffic direction.

1. The object of the invention is to cause speaking connections to be set up as speedily as possible over such switches and with the aid of simple means, this being achieved by an impulse receiver which, when seized, is set automatically to 10 a definite traffic direction, being associated with switching means which, when another traffic direction has been identified, facilitates the setting of the switch thereto.

An embodiment of the invention is shown in 15 the accompanying drawing. Only the circuit details necessary for the complete understanding of the feature of the invention have been shown. The invention is not limited to the embodiment only.

20 Lines leading to another exchange are to be reached in group I over the final selector LW which is constructed as a twenty-five point rotary switch with zero position, whereas group II contains subscribers' lines associated with the 25 change in question. The line L, having the leads a, b, c, may be assumed to extend from a call finder which hunts for a calling subscriber's line in known manner. Each final selector LW is associated with a discriminator M having switch 30 wipers 3d1 and 33d1. This discriminator facilitates the change-over of the final selector from one traffic direction to another. The final selector LW is provided with the switch wipers a—d, a contact bank brushed by the switch wiper d also 35 being used for the change-over of the final selector. This contact bank is provided with the stopping positions x and y.

When a subscriber wishes to set up a connection, the call finder (not shown) is set to the 40 subscriber's connecting line when the receiver is lifted and the final selector LW seizes an idle exchange line at once. The switching operations are as follows: When the call finder has seized the connecting line, the windings I and II of relay A 45 are connected to battery due to the loop of subscriber's line being closed by means of the switch hook, with the consequence that relay A is energized. The opening of contact 1a removes the short circuit for the seizing relay C of the final 50 selector. Contact 30a opens the circuit for the rotary magnet D1 of the discriminator M, while contact 13a short circuits winding I of the slow-acting relay V. Contact 35a opens the circuit for the rotary magnet D of the final selector LW. 55 Contact 51a is located in the circuit of the suc-

ceeding switch. Due to the short circuit for relay C being removed by means of contact 1a, said relay C is energized in the following circuit: earth, battery in the call finder (not shown), c-lead, winding of relay C, contact 2 to (contact of the 60 rotary magnet D of the final selector LW which is shown in the normal position of the final selector only), switch wiper 3d1 of the discriminator M, contact 4a, earth. Relay C, by the closing of its contact 5c, is placed in a locking circuit and, 65 by closing contact 7c, prepares a circuit for the rotary magnet D1 and also, by the closing of contact 9c, a circuit for the rotary magnet D. Contact 14c closes the circuit for winding I of relay V. This relay, however, will not be energized, since contact 13a is closed; that is to say, the relay is short circuited. A circuit for winding II of relay V is prepared over contact 8c. Contact 6c closes the circuit for relay H, thus energizing this relay, which closes its contacts 10h and 70 11h and, at the same time, causes contact 12h to be opened. By the throwing of contact 10h, the interrupter Ue is connected to the rotary magnet D of the final selector LW in the following circuit: earth, interrupter Ue, contact 10h, d-wiper of the final selector LW, winding of the rotary magnet D, battery, earth. The switch is advanced from its normal position and actuated step by step over the segment of its contact bank to which the interrupter is connected over the closed contact 15p. This contact bank corresponds to group I of lines i, e, lines leading to an exchange. When the c-wiper of the final selector LW encounters a free exchange line, the test relay P will be energized in known manner in the following circuit: earth, closed contact 9c, contact 31v, 80 windings II and I of relay P, c-wiper of the final selector LW, battery, earth (to a free exchange line). The test relay P is energized and by means of its contact 15p cuts off the circuit for the rotary magnet D and thus in known manner guards the seized exchange line against other final selectors due to the short circuiting of its high resistance winding II over contact 16p. Contacts 41p and 42p switch through the junction 85 line to the final selector.

The subscriber may now himself, by transmitting impulse series, set the switches in the exchange and complete the required connection. If the first two impulse series sent out (the number of impulse series characterizing the change-over is optional) indicate that the subscriber requires an internal connection, the corresponding change-over of the final selector takes place, said final selector then being set to the corre- 100 105 110

sponding subscriber's connection by means of impulse series. The rotary magnet D1, by means of contact 30a of relay A, is made dependent on said impulse relay, whereas the circuit for the 5 rotary magnet D is intermittently closed by contact 35a. The impulses set up by contact 35a influence the circuit for the rotary magnet D only when contact 26u also is closed.

If, for example, the calling subscriber dials 10 the digit 3, the switch wiper 3d1 sets up the following circuit for relay U1 as relay V releases after each impulse series; earth, contact 4v, wiper 3d1 of the discriminator M, contact 20u1, winding of relay U1, battery, earth. Relay U1 is energized 15 in this circuit and remains energized over its thrown-over light contact 20u1 and the closed contact 11h to earth. The closing of contact 21u1 prepares a circuit for relay U2. When the subscriber now dials the second digit, for example, 20 the digit 6, relay V releases afresh after the impulse output and closes the following circuit for relay U2: earth, contact 4v, switch wiper 3d1, contacts 21u1, 22u2, winding of relay U2, battery, earth. Relay U2 is energized in this circuit, re- 25 mains energized over the light contact 22u and contact 11h and, due to the opening of its contact 40u2, prevents further impulse series from being transmitted over the free exchange line. The throwing over of contact 25u2 closes the circuit 30 for winding II of relay U. Relay U remains energized over its contact 32u and its winding I over contact 9c to earth and closes the following circuit for the rotary magnet D of the final selector LW, over its contact 27u: earth, interrupter Ue, 35 contact 27u, d-wiper of the final selector LW, winding of rotary magnet D, battery, earth. The rotary magnet D is advanced in this circuit until the switch wiper d has left the corresponding 40 segment of its contact bank and encounters the contact located in front of the stopping position x, which contact is connected to the conductor extending to winding II of relay V. The rotary magnet D cannot be energized when winding II of relay V is placed in series therewith, due to the 45 fact that winding II of relay V has a high resistance. As soon as the d-switch-wiper of the final selector LW leaves the segment over which the interrupter Ue was connected up, the c-wiper leaves the group of exchange lines which causes 50 the test relay P to be de-energized. This restores among others the contact 16p to normal with the result that, due to contact 26u being closed, the following circuit for the rotary magnet D of the final selector is intermittently closed 55 when contact 35a of the impulse relay A is closed on the transmission of the succeeding impulse series: earth, contacts 9c, 16p, 26u, 352, winding of the rotary magnet D, battery, earth. Relay A not yet being energized, no operations will 60 result. According to which group of subscribers' lines the calling subscriber requires, he dials either digit 1 or digit 0. When dialling digit 1, he causes the final selector to be set to the stopping position x, and dialling the digit 0 to the 65 stopping position y. The subscriber now dials the last digit, which causes the final selector LW to be set to the required subscriber's line. The advance of the rotary magnet takes place in 70 the circuit just referred to. If the required subscriber's line is idle, the relay P is re-energized, which, due to the open contact 31v, cannot be energized during the impulse series, and opens the circuit for the rotary magnet D by means of 75 its contact 16p and by the short circuiting of its

high-resistance winding sets up the guarding in the manner already described.

The required connection is now completed and conversation may take place. When the calling subscriber replaces his receiver at the end of the 80 call, relay A releases in known manner and, by the short circuiting of relay C with the aid of contact 1a, causes said relay to be released with slow action. The opening of contact 6c causes relay H to be deenergized. The closing of contact 12h restores the final selector LW to normal by means of the interrupter Ue independently whether it has been set to the stopping position x or y or whether it is set to the first of the second group of subscribers' lines. The discriminator returns to its original position over the multiple contact bank of the switch wiper 33d1, since the interrupter Ue also is connected up over this contact wiper and contact 10h in normal position. 95

Instead of the group of exchange lines and the two groups of subscribers' lines, a group of lines may, obviously, be connected to the contact banks of the final selector and lead to another small exchange similar to the type shown. 100

What is claimed is:

1. In an automatic switch having access to two groups of lines, means responsive to the seizure of the switch for causing it to select an idle line in one group, means for responding to impulses 105 and for repeating the impulses over the selected line, and means controlled by said last means for causing the switch to abandon the selected line, take up a position in selective relation to the other line group, and wait in said position for further impulses.

2. In an automatic switch having access to two groups of lines, means responsive to the seizure of the switch for causing it to select an idle line in one group, means for responding to impulses 115 and for repeating them over the selected line, means controlled by said last means for causing the switch to abandon the selected line, and means responsive to directive control for causing the switch to connect with a wanted line in the 120 other group.

3. In an automatic switch having access to two groups of lines, means responsive to the seizure of the switch for causing it to select an idle line in one group, means for responding to a plurality of series of impulses, and means operative dependent upon the value of the first two 125 series of impulses for causing the switch to abandon the selected line, take up a position in selective relation to the second line group, and wait in said position for another series of impulses.

4. In an automatic switch having access to two groups of lines, means responsive to the seizure of the switch for causing it to select an idle line in one group, means for responding to a plurality of series of impulses, and means operative dependent on the value of the first impulse series for rendering the switch directly operable by a subsequent impulse series to connect with a particular line in the other group. 140

5. In an automatic switch having access to a plurality of outlets, means for causing the switch to hunt for and connect with an idle outlet responsive to the seizure of the switch, means for responding to impulses, and means controlled by 145 said last means for converting the switch from a free hunting switch to a directly operable switch.

6. An automatic switch adapted to operate as a free hunting switch responsive to its seizure, 150

to respond to and repeat impulses, and to re-operate subsequently under directive control, all on the same call.

7. An automatic switch adapted to operate initially as a free hunting switch responsive to its seizure, to respond to and repeat impulses, and, dependent upon the value of the impulses, to re-operate directly responsive to further impulses.

10 8. In a telephone system, an automatic switch, trunk lines and subscribers' lines accessible to the switch, means for seizing the switch, means responsive to said seizure for operating the switch to hunt for and connect with a trunk line, means for transmitting series of impulses to the switch, means in the switch for repeating certain of said impulse series over the trunk line connected with, and means in the switch controlled by the value of the repeated impulse series for causing 20 the switch to abandon said trunk and respond to a subsequent series of impulses to select a subscriber's line.

9. In a telephone system, a first switch having access to two groups of lines, a second switch associated individually with the first switch, means for extending a connection to the first switch, means responsive to said connection for operating said first switch to hunt for and connect with an idle line in one group, means for transmitting impulses over said connection to the first switch, means in the first switch for repeating the impulses to the second switch and to the connected line, means controlled by the second switch for causing said first switch to release the connected line and for rendering the second switch non-responsive to further impulses from said repeating means.

10. A telephone system as claimed in claim 9 in which the further impulses directly set the first switch to connect with a wanted line in the other group.
